(57) **CLAIM**

The ornamental design for a display panel with animated graphical user interface, as shown and described.

DESCRIPTION

FIG. 1 is a front view of a first image in a sequence of a display panel with animated graphical user interface; FIG. 2 is a second image thereof; FIG. 3 is a third image thereof; FIG. 4 is a fourth image thereof; FIG. 5 is a fifth image thereof; FIG. 6 is a sixth image thereof; FIG. 7 is a partial enlarged view taken from FIG. 1; FIG. 8 is a partial enlarged view taken from FIG. 2; FIG. 9 is a partial enlarged view taken from FIG. 3; FIG. 10 is a partial enlarged view taken from FIG. 4; FIG. 11 is a partial enlarged view taken from FIG. 5; and, FIG. 12 is a partial enlarged view taken from FIG. 6. The appearance of the graphical user interface transitions sequentially between the images shown in FIGS. 1-6 and FIGS. 7-12. The process or period in which one image transitions to another forms no part of the claimed design. The dot-dash broken lines form a border of the claimed design. The broken lines used to reference the enlarged portions corresponding to differing views and the broken lines showing portions of the display panel form no part of the claimed design.
